FIG. 3

FIG. 2

FIG. 1

Inventor: William Morrison

By Byrnes, Townsend & Sticklen, Atty's

UNITED STATES PATENT OFFICE.

WILLIAM MORRISON, OF CHICAGO, ILLINOIS.

STARTER MECHANISM.

1,261,593.

Specification of Letters Patent. Patented Apr. 2, 1918.

Application filed February 14, 1916. Serial No. 76,236.

To all whom it may concern:

Be it known that I, WILLIAM MORRISON, a citizen of the United States, residing at Chicago, in the county of Cook and State of Illinois, have invented certain new and useful Improvements in Starter Mechanism, of which the following is a specification.

My invention relates to a starting mechanism for internal combustion engines on 10 automobiles and is an improvement on or addition to the arrangements shown in my Patents 1126059, 1126060 and 1126061 patented January 26, 1915; and is adapted for use in connection with the system shown 15 in my Patent 1148788 patented August 3, 1915. In these patents I have shown a double rotor dynamo electric clutch which acts both as a current-generating clutch and an engine starting motor, and this invention relates to this latter use. Its object is to provide 20 a device which shall hold against rotation the rotor connected to the load, and to operate said holding device automatically from the switch or other mechanism which causes current to flow from the battery to the dynamo 25 to operate it as an engine starting motor, so that the holding device shall operate before the motor starts or simultaneously therewith. There is thus prevented the backing 30 of the automobile, which may happen when the operator forgets to apply the brakes to his machine before starting the engine. The invention is also applicable where the second rotor of the dynamo is connected to a 35 rotatable member other than one directly connected to the load.

The invention will be readily understood 40 from the accompanying drawings in which Figure 1 is a diagram and Fig. 2 an elevation of the holding mechanism; and Fig. 3 is a plan of Fig. 2.

Referring to Fig. 1, A is a gas engine, B is the engine shaft secured to one of the rotors of the dynamo; in this case it is shown 45 as connected to the armature C; D is an internal commutator ring against which bear spring-pressed brushes E, carried in brush holders F, secured to the field magnet rotor G, which is secured to the power shaft H, or 50 other rotatable member. Current is delivered to the motor from a battery, L, through wires, 1, and, 2, connected by brushes to rings, I, and, K, on shaft H. In this circuit is a switch M. Mounted on the shaft, 55 H, is a ratchet wheel, N, with which engages a pivoted pawl, O, which is pivoted to

a plunger, P, having at its lower end an armature, Q.

The magnet comprises an outer shell R, and an inner core S. T is the coil to which 60 are connected wires 3, and 4. U is a spring for normally holding the armature in retracted position. The magnet and the pivot for the pawl are secured to the frame of the automobile.

65 The operation of the device will be apparent from the foregoing description, and is as follows:

When the switch M is closed, current flows 70 from battery L, through wire 3 to coil T, wire 4, and back to the battery. Thereupon the armature Q, is pulled up and causes the pawl, O, to engage the teeth of the ratchet wheel, N, and block any tendency 75 to rotate in the wrong direction. As the ratchet-wheel, N, is fast on shaft H, this shaft and the dynamo field carried thereby are also blocked against rotation. The closing of switch, M, also delivers current 80 through wires, 1, and, 2, to the dynamo which thereupon operates as a motor and starts the engine. After the engine is running, the switch M is opened. The magnet T is thereby deenergized, and the spring U raises the pawl from its engagement with 85 ratchet N. The proper circuit connections for operating the dynamo as an electromagnetic clutch are then made, as described in my patents above referred to.

The electrical conditions of the circuits 90 are so arranged that the holding device is operated before, or simultaneously with, the starting of the motor, so that there is no possibility of rotating backwardly the load-shaft H, which if permitted would back the 95 automobile.

I have shown the form of holding mechanism which I am using in practice, and which has been found to be entirely satisfactory, but obviously other holding means 100 might be used. So also, I have shown a simple diagrammatic switch and circuit arrangement, which may readily be varied by those skilled in the art, while still obtaining the desired result, which is,—to absolutely prevent by automatic means, any danger of backing the automobile when starting the engine. There is no possibility of the operator, as in a garage or crowded street traffic, backing his car by forgetting 110 to apply his brakes before starting the engine.

I claim.

1. In an engine-starting mechanism, an internal combustion engine, a double rotor dynamo having one rotor connected to the engine and the other to a rotatable member, a battery in circuit with the dynamo, mechanism for holding against rotation the rotor connected to the rotatable member, a switch in the dynamo circuit and means coördinated 10 with said switch to automatically operate the holding mechanism not later than the starting of the dynamo.

2. In an engine-starting mechanism, an internal combustion engine, a double rotor dynamo having one rotor connected to the engine and the other to a rotatable member, a battery in circuit with said dynamo, electromagnetically operated means for holding against rotation the rotor connected to the 15 rotatable member, a circuit connecting the battery and the electromagnet, and switching mechanism arranged to automatically cause operation of the holding mechanism not later than the starting of the dynamo.

3. In an engine-starting mechanism, an internal combustion engine, a double rotor dynamo having one rotor connected to the engine and the other to a rotatable member, electromagnetically operated means for 20 holding against rotation the rotor connected to the rotatable member, a battery in electrical connection with the dynamo and the electro-magnet, and a switch for controlling said electrical connection whereby the holding mechanism will be automatically operated 25 not later than the starting of the dynamo.

4. In an engine-starting mechanism, an internal combustion engine, a double rotor dynamo having one rotor connected to the engine and the other to a rotatable member, a battery in circuit with the dynamo, mechanism for holding against rotation the rotor connected to the rotatable member, a switch in the dynamo circuit and means coördinated 40 with said switch to automatically operate the holding mechanism.

5. In an engine-starting mechanism, an internal combustion engine, a double rotor dynamo having one rotor connected to the engine and the other to a rotatable member, a battery in circuit with said dynamo, electromagnetically operated means for holding against rotation the rotor connected to the rotatable member, and switching mechanism 50 controlling the circuit of said battery and dynamo and of said holding means.

6. In an engine-starting mechanism, an internal combustion engine, a double rotor

dynamo, having one rotor connected to the engine and the other to a rotatable member, 60 electromagnetically operated means for holding against rotation the rotor connected to the rotatable member, a battery in electrical connection with the dynamo and the holding means, and a switch for controlling 65 said electrical connection.

7. In a system of propulsion, the combination of an internal combustion engine, a dynamo electric machine, one member of which is connected to the engine and the 70 other to the load, an external source of current supply, means acting in response to current flow for preventing the member connected to the load from turning during the starting operation, and means adapted to admit current from the source to said means to prevent the member which is connected to the load from turning, and to admit current to said members to permit the reactive effect 75 between them to rotate the engine shaft for starting purposes.

8. In an engine-starting mechanism, an internal combustion engine, a dynamo electric machine, one member of which is connected to the engine, and the other to a rotatable member, an external source of current supply in circuit with the dynamo, mechanism for holding against rotation the rotor connected to the rotatable member, means for controlling the dynamo circuit, 80 and means coördinated with said controlling means to automatically operate the holding mechanism.

9. In an engine-starting mechanism, an internal combustion engine, a double rotor 95 dynamo having one rotor connected to the engine shaft and the other to a rotatable member, a ratchet wheel on the rotatable member, a pawl, an electromagnet connected to the pawl to cause engagement with the 100 ratchet wheel, a spring for disengaging the pawl, and an external source of current in circuit with the dynamo and electromagnet.

10. In an engine-starting mechanism, an internal combustion engine, a dynamo electric machine, one member of which is connected to the engine and the other to a rotatable member, an external source of current supply, means for holding against rotation the member of the dynamo electric machine 110 connected to the rotatable member, a starting switch, and means for insuring the operation of said holding means when the engine is started.

In testimony whereof I affix my signature. 115
WILLIAM MORRISON.
